UNITED STATES PATENT OFFICE.

ARNOLD J. BROUYETTE, OF SHADYSIDE, OHIO.

TONGS.

1,013,122.

Specification of Letters Patent.

Patented Jan. 2, 1912.

Application filed May 10, 1911. Serial No. 626,231.

To all whom it may concern:

Be it known that I, ARNOLD J. BROUYETTE, a citizen of the United States of America, residing at Shadyside, in the county of Belmont and State of Ohio, have invented certain new and useful Improvements in Tongs, of which the following is a specification, reference being had therein to the accompanying drawing.

10 This invention relates to tongs particularly designed for lifting fire, hot coals and fuel.

The primary object of my invention is to furnish a shovel with a gripping arm or 15 tongs that will coöperate with the shovel in lifting hot coals or fuel, the device being particularly designed for open hearths or fire places.

Another object of my invention is to provide a short handled shovel that can be easily converted into a long handled shovel.

A further object of the invention is to provide a pair of tongs that is simple in construction, durable, inexpensive to manufacture and easy to manipulate.

The above objects are attained by a mechanical construction that will be herein-after specifically described and then claimed.

Reference will now be had to the drawing, wherein:—

Figure 1 is a perspective view of the tongs, Fig. 2 is a longitudinal sectional view of the same, Fig. 3 is a side elevation of the tongs, partly broken away, and Fig. 4 is a sectional elevation of a portion of the tongs.

The reference numeral 1 denotes a shovel having side walls 2 and a short tapering handle 3, said shovel being preferably stamped or pressed from a single sheet of metal. The handle 3 is channel-shaped and at the end thereof the side walls are provided with oppositely disposed openings 3^a.

The reference numeral 4 denotes a tapering gripping arm that is semi-cylindrical in cross section and has the lower edges thereof bent inwardly to provide oppositely disposed flanges 5, said flanges forming a slot 6 extending from the rear end of said arm to a point approximate to the forward end thereof. The forward end of the arm is bent and slotted to provide gripping teeth

7, and is punched with the punched material bent downwardly to form a lip 8, for a purpose that will presently appear.

Arranged in the openings 3^a of the handle 3 is a transverse rivet or bolt 9 and pivotally mounted upon said rivet or bolt is the depending tongue 10 of the member 11, said member loosely engaging in the arm 4. The member is preferably made of a single piece of material and the lower forward edge thereof provided with an extension 12 under which engages the rear end of a flat spring 13 riveted or otherwise connected to the inner side of the handle 3, as at 14. The member 11 is adapted to slidably support the arm 4, whereby said arm can be shifted longitudinally of the handle 3, besides pivotally supporting the arm whereby the forward end thereof can be raised and lowered relatively to the shovel 1.

Soldered or otherwise secured to the handle 3 adjacent to the shovel 1 is a retaining member 15 and adjacent to said retaining member is a flat spring 16 having a thumb piece 17. The spring is soldered or otherwise connected to the handle and is adapted to retain the toothed end of the arm 4 under the member 15, the lip 8 engaging the end of the spring 16 and preventing a rearward movement of the arm 4 until the spring is lowered by the thumb piece 17. The rear end of the arm 4 is provided with an eye or link 18, whereby the tongs can be suspended from a nail or other support.

The entire device can be made of light and durable metal and finished to present a neat appearance. It can also be made of various sizes and utilized for other purposes than herein specified.

What I claim is:—

A device of the character described comprising a shovel, a handle having its rear end slotted, a hollow gripping arm arranged over said handle and having its forward end toothed and its bottom slotted, a coupling member pivotally mounted in the rear end of the handle, extending up through said slot of the handle into said gripping arm and having its upper portion conforming in contour to the shape of said gripping arm, 10 said arm capable of being shifted longi-

tudinally upon said handle, a spring fixed at one end to the handle and adapted to engage said coupling member for maintaining the forward end of the arm elevated with respect to said shovel, and means carried by the handle and adapted to engage the forward end of said arm and further adapted to extend into said arm for maintaining the arm in abutting engagement

with the handle against the action of said spring.

In testimony whereof I affix my signature in the presence of two witnesses.

ARNOLD J. BROUYETTE.
